DECOUPLING MOUNTING PLATE FOR
TUNING FORKFrank Dostal, Elmhurst, N.Y., assignor to Bulova Watch
Company, Inc., New York, N.Y., a corporation of
New YorkFiled Nov. 24, 1965, Ser. No. 509,510
7 Claims. (Cl. 331—116)

This invention relates generally to tuning-fork oscillators, and more particularly to an improved mounting plate for a tuning fork, which plate has a compliance characteristic effectively isolating the fork from the mounting plate with respect to the vibratory forces, whereby the fork frequency is precisely maintained.

Tuning-fork oscillators have many practical applications, and are currently used as frequency standards, for power-line regulation, in guidance systems and geophysical instruments, as tuned filters, and as driving elements for optical modulators and in timing devices. The operating frequency of a vibratory fork is determined by the tine dimensions, the frequency being directly proportional to the thickness of the tines and inversely proportional to the square of their length.

The utility of a tuning-fork oscillator depends on its frequency stability, and it is essential therefore, that the fork operate at a constant frequency even when the fork is employed in an environment which subjects the fork to external shocks such as in a jet plane, a tank, a destroyer, or other moving vehicle. The utility of a tuning-fork oscillator also depends on its operating frequency, and there is a growing need for forks operating on the high frequency range, that is in the range 3000 cycles per second.

A tuning-fork oscillator is a system constituted by three masses which are elastically coupled, the first two masses being the tines and the third being the mounting fixture for the fork. In order for the fork to operate at a predetermined frequency, the masses and elasticities must remain constant. There is a tendency, however, particularly in high-frequency forks, for spurious oscillations to be excited in the mounting plate, as a consequence of which the fork operation, frequency and stability are adversely affected.

Thus the fork system is effectively altered from a normal system constituted by three masses and two elasticities, to an abnormal system having an additional elasticity by reason of mounting plate elasticity. The third mass and third elasticity are therefore a source of difficulty, for they contribute unknown components to the basic frequency-determined masses and elasticities.

The tines of a tuning fork vibrate in phase opposition at a frequency determined by the parameters of the system. The ends of the tines execute an arcuate motion in the course of vibration, the motion producing a secondary component of motion which is developed in a direction along the axis of the fork and at a frequency twice that of the tines. The reason for this is that the arcuate motion of the tines includes an axial vector, and inasmuch as each tine traverses its zero position twice in the course of a vibratory cycle, the axial frequency is double the tine frequency.

In a conventional mounting arrangement wherein the fork is rigidly mounted, the axial component is transmitted to the mounting plate, as a result of which the plate is excited and the stability of the fork is disturbed. The excitation of the plate by other components of fork vibration can be nulled out by carefully balancing the tines of the fork, but even when the tines are balanced, the axial component will be transmitted to the mounting plate.

2

It is known to provide tuning forks with mounting stems resiliently joined to the base of the fork or to provide resilient supports for the fork, but while such expedients are effective to decouple the fork from the mounting with respect to transversely-directed components of fork motion, they are ineffective as to the axial component.

Accordingly, the main object of the invention is to provide a mounting plate for a tuning fork, the plate having a compliance characteristic which permits the fork to vibrate axially, but which at the same time acts to effect optimum decoupling of the mounting and the fork with respect to the axial component. Thus the mounting plate in accordance with the invention serves to isolate the third mass and third elasticity as to maintain the desired operation, frequency and stability of the fork.

A significant feature of the invention is that it is especially effective in preventing the excitation of spurious vibrations in a mounting plate when the fork operates in the high-frequency region. An advantage of this feature is that it now becomes possible to make precision frequency forks in a range going as high as 25 kilocycles per second, whereas it was heretofore difficult or impossible to make precision forks with frequencies as high as 3 kilocycles.

Briefly stated, these objects are attained in a mounting plate having an aperture which is bridged by two bendable beams in parallel relation, the beams being joined by a platform on which is mounted the tuning fork in a manner whereby the tines of the fork lie in a plane parallel to the plane of the mounting plate and the longitudinal axis of the fork is perpendicular to the axis of the beams.

The mass of the fork and the elasticity of the compliance provided by the bendable beams are such as to establish a frequency which is less than twice the fork frequency, whereby the fork is effectively decoupled from the mounting with respect to the axial component of vibration. The beam arrangement is also such as to provide rotational compliance as well, thereby decoupling the fork and mounting plate with respect to non-axial components of vibration.

For a better understanding of the invention, as well as other objects and further features thereof, reference is made to the following detailed description to be read in conjunction with the accompanying drawing, wherein:

FIG. 1 is a plan view of a compliant mounting plate in accordance with the invention;

FIG. 2 shows a plug-in type of tuning-fork oscillator, in plan view, with a tuning fork supported on the mounting plate;

FIG. 3 is an end view of the oscillator;

FIG. 4 illustrates in perspective a detail of the drive coil of the oscillator; and

FIG. 5 schematically shows the oscillator circuit.

Referring now to the drawing, there is shown a tuning-fork oscillator in accordance with the invention, the oscillator including a tuning fork, generally designated by letter T, a mounting plate M therefor, a pickup coil L₁, a drive coil L₂, and an output coil L₃. The above-listed components are protectively housed as an assembly within a casing C provided with a multi-terminal plug P adapted to provide a plug-in connection for the coils to their associated electronic elements.

In the practical embodiment shown, the tuning fork was designed to operate at a fundamental mode of 9400 cycles per second, this frequency being determined by the dimensions of tines 10 and 11. As pointed out previously, the present invention makes it possible to provide precision tuning-fork oscillators operating at frequencies as high as 25,000 cycles. To minimize the effect of temperature on frequency, the fork is preferably made of such ferromagnetic alloys as "Ni-Span" and "Vibral-

loy," to produce low-temperature coefficients. Alternatively, one may use a bi-metallic fork composed of lamine having a positive and negative coefficient.

The tines 10 and 11 of the fork project upwardly from a base 12 provided with an internal mounting stud 13 extending midway between the tines. The internal mounting stud serves to mount the fork at its center of moment, thereby considerably reducing the effects of shock and vibration thereon, as well as shortening the over-all length of the fork, as compared to an external mounting stud.

The mounting plate M, which may be formed of aluminum, is rectangular in form, and includes a generally rectangular central aperture 14 which is bridged by two bendable beams 15 and 16 disposed in a parallel relation, the beams being interconnected by a transverse platform 17. In practice, the beams and platform may be integral members formed by cutting suitable slots in a solid plate to define these elements.

The tuning fork is mounted on the plate by two screws 18 and 19 which join the stud 13 to platform 17, a spacer 20 being interposed between the stud and the platform whereby the tuning fork is disposed in a plane parallel to the plane of the mounting plate, and the tines of the fork are normal to the longitudinal axes of beams 15 and 16.

Mounting plate M is supported on isolation blocks 21 and 22 carried on a base plate 23 resting within the casing C on pillars 24. The blocks are of a material having high flexibility and mechanical damping properties, such as foamed polyurethane.

Characteristic coil L₂, as best seen in FIG. 4, is an electromagnetic element constituted by two L-shaped pole-pieces 25 and 26 forming an air gap 27, the pole-pieces being fabricated of soft iron or Permalloy, and being joined together by a permanent magnet member 28 surrounded by a winding 29. The air gap 27 is positioned adjacent tine 11, whereby when the coil L₂ is energized by a pulse of current, the resultant magnetic field acts on the tine to excite vibration therein. Pickup coil L₁ is identical in design to coil L₂, such that when tine 11 vibrates, it induces a voltage in the coil. Coil L₃ is also of the same design, but it is disposed adjacent the base of the fork, for reasons to be later explained.

As shown in FIG. 5, drive coil L₂ is connected in the emitter-collector circuit of a transistor 30 in series with battery 31, the pickup coil L₁ being connected in the base emitter circuit through a resistance-capacitance biasing net work 32 to a transistor amplifier having a gain in the order of a few hundred times. The arrangement is such that the transistor is normally biased to cut-off, but is rendered momentarily conductive by a voltage induced in pickup coil L₁, by the vibration of tine 11. When the transistor is conductive, a current impulse passes through the drive coil L₂, which actuates tine 10, this process being repeated cyclically to maintain the fork in vibration. Thus currents induced in pick-up coil L₁ due to one tine motion are amplified and applied to drive coil L₂, thus maintaining the fork in vibration.

The transistor drive arrangement for the fork forms no part of the present invention, and the fork may also be maintained in operation by vacuum-tube circuits or other means conventionally used for driving a tuning fork.

When the tines 10 and 11 of the fork vibrate along an arcuate path, an axial component of motion is produced which is transmitted toward the base 12 along the axis extending along stud 13 and represented by line X in FIG. 5. In the event the mounting of the fork were rigid, this axial motion would in turn be transmitted to the mounting plate, with the adverse effect previously noted. However, the fork is supported on beams 15 and 16, which impart axial compliance to the mounting along axis X. The degree of compliance provided by the elasticity of the beams is made such with respect to the mass of the fork supported thereon as to establish a frequency which is less than twice the fundamental fre-

quency of the fork. Hence, the frequency of the compliant mounting is non-resonant with respect to that of the fork, and the fork and the mounting are effectively decoupled in regard to the axial component of fork motion. Because of the difference in the frequency of the fork and the frequency characteristic of the mounting, the vibration of the fork in the axial direction does not act to produce parasitic oscillations in the mounting.

The compliant mounting is also capable of rotation about the point of intersection between an axis Y perpendicular to the X-axis and midway between beams 15 and 16, so as to decouple the fork from the mounting with respect to non-axial components of fork motion which are not otherwise completely balanced out.

Thus the efficiency of the fork is maintained at its optimum value and its stability is not adversely affected by the mounting therefor, nor by external shocks, for the fork is also isolated from such shock. While it is sufficient that the resonance of the compliant mounting, with the fork in place, be under twice the fork frequency, the stiffness must be maintained sufficiently high so that external vibrations, such as that produced by jet aircraft, induced along the tine axis do not themselves excite resonance.

It will be noted that the oscillator has two outputs, the first of which OUT-I is derived from pick-up coil L₁ and has a stable frequency determined by the tine frequency, and the second of which OUT-II is derived from coil L₃ and is twice the tine frequency. As pointed out previously, the base of the fork has a vibratory component transmitted thereto which is double the tine frequency and it is this harmonic component which is picked up by coil L₃.

While there has been shown a preferred embodiment of mounting plate for tuning fork in accordance with the invention, it will be appreciated that many changes and modifications may be made therein without, however, departing from the essential spirit of the invention as defined in the annexed claims.

What is claimed is:

1. A precision tuning-fork oscillator comprising:
  - (a) a tuning fork having a pair of tines interconnected by a base and extending therefrom in a common plane, said base having a mounting stud projecting therefrom,
  - (b) means to sustain said fork in vibration at the natural frequency of said tines, the motion of said tines producing an axial component of motion which is transmitted to said stud,
  - (c) a mounting plate for supporting said fork, said plate having a rigid portion for securing said plate to a fixture and a compliant portion resiliently connected to said rigid portion,
  - (d) and means securing the stud of said fork to said compliant portion to dispose the plane containing said tines in parallel relationship to the plane of said mounting plate, the compliant portion of said plate having a value of elasticity which in combination with the mass of said fork establishes a frequency which is less than twice the natural frequency of the fork.

2. An oscillator as set forth in claim 1, wherein said stud projects upwardly from said base between said tines to provide a relatively short fork.

3. An oscillator as set forth in claim 1, wherein said means to sustain said fork in vibration includes a fixed drive coil operatively coupled to one of said tines, a fixed pickup coil operatively coupled to the other of said tines, and a transistor circuit whose input is coupled to the pickup coil and whose output is coupled to the drive coil to apply pulses thereto under the control of voltages induced in said pickup coil.

4. An oscillator as set forth in claim 1, including a fixed output coil operatively coupled to the base of said fork to produce an output voltage whose frequency is twice the natural fork frequency.

5. An oscillator as set forth in claim 1, wherein said mounting-plate compliant portion is formed by an aperture which is bridged by a pair of bendable beams in parallel relationship, the beams being interconnected at their intermediate portions by a platform, said fork stud being secured to said platform.

6. An oscillator as set forth in claim 5, wherein said beams and platforms are integral members formed by slots cut into a solid plate.

7. In a precision tuning fork oscillator, the combination of a tuning fork having a pair of tines extending from a base provided with an internal mounting stud, and a mounting plate for said fork which includes a pair of

bendable beams bridging a central aperture in said plate and a platform transversely spanning said beams, said stud being attached to said platform to support said fork in a plane parallel to said plate, the compliance afforded by said beams having an elasticity which in combination with the mass of said fork establishes a frequency lower than the natural frequency of the fork.
